UNITED STATES PATENT OFFICE.

RINO PARISI, OF RIMER, PENNSYLVANIA.

CURTAIN AND OPERATING MEANS THEREFOR.

Application filed November 30, 1927. Serial No. 236,777.

This invention relates to curtains and more particularly to a set of curtains adapted to be mounted at opposite sides of a window and moved across the window 5 toward each other into closing relation to the window.

One object of the invention is to provide curtains having their rollers rotatably mounted at opposite sides of a window and 10 improved means to rotate the rollers and move the curtains toward and away from each other and prevent the curtains from moving out of a set position.

Another object of the invention is to 15 cause the curtains to be simultaneously operated in proper timed relation to each other and cause the rollers to be rotated at such speed that the curtains may be freely unwound when moved into closing relation 20 to a window and evenly wound upon their rollers when moved away from each other.

Another object of the invention is to permit both of the curtains to be simultaneously 25 adjusted by rotating a shaft which may be referred to as an operating shaft and has operative connection with both of the curtains.

Another object of the invention is to provide brackets of an improved construction 30 by means of which the rollers may be rotatably mounted and retained in a vertical position but permitted to be easily removed when necessary.

The invention is illustrated in the accompanying drawing, wherein

Fig. 1 is a view in elevation showing the improved curtains applied to a window;

Fig. 2 is a fragmentary top plan view of the improved curtain structure;

Fig. 3 is a fragmentary view partially in elevation and partially in section and illustrating the manner of rotatably mounting the upper end of one curtain roller;

Fig. 4 is a transverse sectional view taken 45 on the line 4—4 of Fig. 1, and

Fig. 5 is a sectional view taken on the line 5—5 of Fig. 4.

The improved curtains and operating means therefor constituting the subject- 50 matter of this invention has been illustrated in operative relation to a window including a frame 1 and sashes 2, but it will be understood that the curtains could be applied to a doorway in which case they could serve as 55 portières. They could also be employed as a partition by means of which a portion of

a room could be temporarily shut off from the remainder of the room.

The two curtains which are indicated by the numerals 3 and 4 are of a duplicate construction and each includes a roller 5. The rollers extend vertically at opposite sides of the window frame and have pintles or shafts 6 which project from their upper and lower ends and are engaged with the bearing brackets 7. These brackets are preferably formed of sheet metal and each includes an attaching flange 8 adapted to be firmly secured against the window frame and an arm 9 which projects outwardly from the window frame and is formed with a recess or pocket 10 leading from one side. The shafts or pintles of the rollers are rotatably received in the pockets 10 of the brackets and each is retained in the pocket in which it is received by a latch 70 strip 11 which is pivoted to the arm 9, as shown at 12, and has its other end portion formed with a tooth 13 adapted to be snapped into a socket 14 formed in the bracket. Therefore, the rollers will be rotatably 80 mounted and prevented from moving out of proper engagement with their brackets but when it is desired to substitute new curtains for those already in use the latches may be easily released in order to permit the rollers 85 to be removed from the brackets and the new ones set in place.

Rods 15 which extend vertically along the free ends of the curtains are connected with the curtains by clips 16, and these rods have their end portions projecting above and below the curtains, as shown in Fig. 1. Internally threaded sleeves 17 are carried by the rods in crossed relation to either end, and these sleeves have threaded engagement 90 with shafts 18 and 19 which extend horizontally across the upper and lower portions of the window frame adjacent the upper and lower ends of the rollers. Each of the shafts has right and left hand threads leading from its ends and the sleeves are threaded in accordance with the threading of the portions of the shafts upon which they are mounted. It will thus be seen that, when the shafts are rotated, the sleeves carried by the rod 15 of the curtain 3 will be moved along the shafts in a direction opposite to the movement of the sleeves carried by the rod of the curtain 4. Therefore, the curtains will be moved toward or away from each other according to the direction in which the shafts are rotated. Bearing brackets 18 are pro- 100 105 110

vided to rotatably mount the shafts 19 and 20 and the end portions of the shafts project from the brackets and carry beveled gears 21 which mesh with cooperating beveled gears 22 secured upon the ends of the pintles 6. By this arrangement the shafts and curtain rollers will be simultaneously rotated when rotary motion is imparted to the shaft 20 through the medium of its crank 23 and the 10 curtains will be moved toward or away from each other according to the direction in which the shafts are rotated.

When the improved curtains are in use, they are applied to a window frame, as 15 shown in Fig. 1, with the curtain rollers disposed vertically at opposite sides of the window frame and the shafts 19 and 20 extending across the upper and lower portions of the window. When the crank 23 is 20 turned to rotate the shaft 20, which may be referred to as a drive shaft, the gears 21 carried thereby will impart rotary motion to the curtain rollers through the medium of the gears 22 at the lower ends thereof 25 and the gears at the upper ends of the curtain rollers will transmit rotary motion to the upper shaft 19 through the medium of the gears at its ends. Therefore, the two rollers and the shafts will be rotated at the 30 same rate of speed. As the shafts rotate, the sleeves 17 will be moved longitudinally upon the shafts at the same rate of speed and in such timed relation to rotation of the rollers that the curtains will be retained 35 under slight tension and, therefore, held smooth and caused to be rolled smoothly upon the rollers when moved away from each other and prevented from wrinkling when moved toward each other into covering 40 relation to the window. By this arrangement the curtains may be easily moved into and out of covering relation to the windows and prevented from having movement if the window is open. This will prevent 45 the curtains from being damaged by wind blowing them. While I have shown the shaft 20 rotated by means of a crank, it will be understood that any means desired may be substituted for the crank.

Having thus described the invention, I 50 claim:

1. In a structure of the character described, vertically disposed rollers, means to rotatably mount the rollers at opposite sides 55 of a passage, curtains wound upon said rollers and when unwound therefrom having movement towards each other across the opening, rods connected with the free ends of the curtains and projecting above and below the same, internally threaded sleeves carried by said rods, shafts each having oppositely threaded portions, means to rotatably support said shafts above and below 60 said rollers, said sleeves being threaded upon 65 adjacent shafts, means to impart rotary motion to

one shaft, and interengaging gears carried by the shafts and rollers whereby when the last-mentioned shaft is rotated the rollers will be simultaneously rotated and the curtains moved into and out of closing 70 relation to the passage.

2. In a structure of the character described, vertically disposed rollers, means to rotatably mount the rollers at opposite sides of a passage, curtains wound upon said rollers and when unwound therefrom having movement towards each other into closing 75 relation to the opening, internally threaded sleeves connected with the free ends of said curtains and disposed above and below the same, shafts extending horizontally above and below said curtains and each having oppositely threaded portions passing through adjacent sleeves in threaded engagement therewith to move the curtains towards and 80 away from each other when the shafts are rotated, intermeshing gears carried by the shafts and rollers, and means to impart rotary motion to one shaft.

3. In a structure of the character described, vertically disposed rollers having pintles extending from their ends, gears carried by said pintles, brackets adapted to be secured to a window frame at opposite sides thereof and having arms projecting from the window frame and formed with pockets leading from their sides and rotatably receiving the pintles to rotatably mount the rollers at opposite sides of the window, latches pivotally carried by said arms and when in a closed position extending across the pockets to retain the pintles therein, curtains wound upon said rollers, rods connected with the free ends of the curtains and having their ends projecting above and below the curtains, shafts extending horizontally above and below said curtains and each having oppositely threaded portions, bearing brackets rotatably securing said shafts and adapted to be secured to the window frame, gears carried by said shafts and meshing with the gears of said pintles whereby the shafts and rollers will rotate in unison when one shaft is rotated, means to 90 impart rotary motion to the said shaft, and internally threaded sleeves carried by said rods at their ends and engaged upon the oppositely threaded portions of the shafts whereby the curtains will be moved relative 95 to each other when the shafts and rollers are 100 rotated.

4. In a structure of the character described, rollers, curtains wound upon said rollers, pintles projecting from the ends of said rollers, bearing brackets having attaching flanges adapted to be secured to a window frame and arms projecting from the flanges and formed with pockets leading from their sides to receive the pintles and 105 rotatably mount the rollers, resilient latch 110

strips carried by said arms and movable from an open position to a closed position extending across the pockets to retain the pintles therein, shafts each having oppositely threaded portions, bearing brackets for said shafts adapted to be secured to the window frame, cooperating gears carried by the shafts and pintles, and internally threaded sleeves connected with the free ends of the curtains and engaged upon the threaded shafts to move the curtains relative to each other when the shafts and rollers are rotated.

5. In a structure of the character described, rollers, curtains wound upon said

rollers, pintles projecting from the ends of said rollers, bearing brackets engaged with said pintles to rotatably mount said rollers at opposite sides of a window, threaded shafts rotatably mounted and extending between the rollers, intermeshing gears carried by the shafts and rollers to effect simultaneous rotation of the rollers when rotary motion is imparted to one shaft, and means carried by the free ends of said curtains and engaged with said shafts to move the curtains towards and away from each other when the shafts are rotated.

In testimony whereof I affix my signature.
RINO PARISI. [L. s.]
